J. H. S.

UNITED STATES PATENT OFFICE

SAMUEL J. LAVEZZI, OF CHICAGO, ILLINOIS

CLIP

Application filed October 16, 1929. Serial No. 399,995.

My invention relates to clips and more particularly to devices of this character which are employed for the attachment of springs to the marginal wire or rattan frame in upholstered furniture, cushioned seats, bed springs, and kindred structures.

The principal object of my invention is to devise a clip of the above nature which is characterized by simplicity in construction, ease of application to the parts to be attached, strength and rigidity for the performance of its primary purpose, which affords an adequate bearing support for such parts, and which does not require any special tools to apply the same.

A further object is to devise a clip which is susceptible of manufacture as a stamping at a low unit cost and which presents a substantially smooth exterior when in securing position.

The present invention is intended as an improvement on the spring attaching clip described and claimed in my United States Letters Patent, No. 1,065,614, dated June 24, 1918, particularly in respect of a simplification in and strengthening of structure, and ease of application in an operative environment. The invention also contemplates the use of a clip which is entirely free from openings through the body thereof and of any necessity for a special attaching tool.

These and further objects of my invention will be set forth in the following specification, reference being had to the accompanying drawing, and the novel means by which said objects are effectuated will be definitely pointed out in the claims.

In the drawing:—

Figure 1 is a perspective view of my improved clip.

Fig. 2 is also a perspective view of the clip, showing the first step in the application thereof to a spring.

Fig. 3 is also a perspective view, showing the second step in the application of the clip to a spring.

Fig. 4 is an enlarged, front elevation of the clip, showing the same in securing relation on a spring and a marginal wire or rattan frame.

Figs. 5 and 6 are sections along the lines

5—5 and 6—6, respectively, looking in the direction of the arrows.

The numeral 10 represents my improved clip which is preferably formed as a stamping and made from any suitable bendable material. The clip 10 comprises a body portion 11 having a pair of spaced, tongue extensions 12 and a tab 13 which is located between said tongues and preferably offset from the plane of the body portion 11.

Assuming that the clip is utilized to secure adjacent portions of a spring and a marginal wire frame, the clip 10 will first be placed over a portion of the wire 14 composing the

spring with the tongues 12 and tab 13 straddling said wire. The tab 13 will then be bent snugly around said wire, as shown in Fig. 2, whereupon the tongues 12 will also be bent around said wire from the opposite side thereof and folded to place the free ends thereof into substantially contiguous relation with the body portion 11, as shown in Fig. 3. It will be apparent, therefore, that the clip encircles the wire 14 in three distinct locations with manifest advantages in the nature of the attachment. The position relation of the body portion 11 and the portions of the tongues 12 remaining after the latter have been bent around the wire 14 establish a bendable unit which is employed to effectively grip the portion of the wire 15 of the marginal frame, said wire being placed against the tongue portions indicated, whereupon the unit noted above is bent around said wire to assume the position shown in Fig. 5.

The gripping of the wire 15 is accomplished by a member which is characterized by a dual thickness over a large part of its area, being created by the body portion 11 and tongues 12, a factor which greatly increases the strength and rigidity of the clip when in securing position. In addition, the use of a pair of spaced extensions further improves the securing quality of the clip owing to its adequate bearing engagement with the parts connected, effectively preventing any rocking tendency. The tab 13, in addition to serving as a securing element between the parts connected, also functions to initially position the clip on one of the connected parts and there-

by enables the clip to be more positively gripped in position. The clip is free from holes of any kind and may be efficiently placed in position with the use of pliers or any similar tool.

While I have shown one set of elements and combinations thereof for effectuating my improved clip, it will be understood that the same is intended for purposes of illustration only and in no wise to restrict my appliance to the exact forms and structures shown, for many changes may be made therein without departing from the spirit of my invention, including the elimination of one of the tongues and/or the tab.

I claim:

1. The combination with two separate parts, of a clip for connecting said parts together comprising a body portion having an extension and a short tab encircling one of the parts with the free end of the extension located in substantially contiguous relation with said body portion and said body portion and free end encircling the other part as a unit.

2. The combination with two separate parts, of a clip for connecting said parts together comprising a body portion having an extension and a short tab encircling one of

30 the parts from opposite sides thereof with the free end of the extension located in substantially contiguous relation with said body portion and said body portion and free end encircling the other part as a unit.

35 3. The combination with two separate parts, of a clip for connecting said parts together comprising a body portion having two spaced extensions encircling one of the parts with the free ends of the extensions located in substantially contiguous relation with said body portion and said body portion and free ends encircling the other part as a unit.

40 4. The combination with two separate parts, of a clip for connecting said parts together comprising a body portion having two spaced extensions and a short tab encircling one of the parts with the free ends of the extensions located in substantially contiguous relation with said body portion and said body portions and free ends encircling the other part as a unit.

45 5. The combination with two separate parts, of a clip for connecting said parts together comprising a body portion having two spaced extensions and a short tab encircling one of the parts from opposite sides thereof with the free ends of the extensions located in substantially contiguous relation with said body portion and said body portion and free ends encircling the other part as a unit.

60 6. The method of securing two parts together consisting in forming a substantially flat clip having a body portion provided with an extension and a short tab offset from the plane of the clip, seating the clip on one of

the parts with the extension and tab on opposite sides thereof, bending said tab and extension around one of said parts to place the free end of the extension in substantially contiguous relation with said body portion, 70 thereby forming a bendable unit, and then bending said unit around the other of said parts.

7. The method of securing two parts together consisting in forming a substantially flat clip having a body portion provided with an extension and a short tab, bending said extension and tab around one of said parts to place the free end of the extension in substantially contiguous relation with said body portion, 75 thereby forming a bendable unit, and then bending said unit around the other of said parts.

8. The method of securing two parts together consisting in forming a substantially flat clip having a body portion provided with two spaced extensions, bending said extensions around one of said parts to place the free ends thereof in substantially contiguous relation with said body portion, thereby forming a bendable unit, and then bending said unit around the other of said parts.

In testimony whereof, I have subscribed my name.
